UNITED STATES PATENT OFFICE.

FRED A. READ AND ELISHA J. TOWLE, OF LYNN, MASSACHUSETTS.

CLUTCH.

1,288,192.

Specification of Letters Patent. Patented Dec. 17, 1918.

Application filed October 16, 1917. Serial No. 196,950.

To all whom it may concern:

Be it known that we, FRED A. READ and ELISHA J. TOWLE, citizens of the United States of America, and residents of Lynn, in the county of Essex and the State of Massachusetts, have invented certain new and useful Improvements in Clutches, of which the following is a specification.

This invention relates to driving mechanisms for machines and particularly to devices of this character in which a motor is connected directly to the main driving shaft of the machine.

The object of the present invention is to provide means between the motor and the machine of a quickly acting connector whereby the machine may be driven at full speed from the motor as soon as the connection is made.

20 The invention consists of an electro-magnet secured to the driving shaft of the machine and adapted when energized to coact with a slidable member keyed to the motor shaft thereby providing means whereby 25 power may be transmitted from the motor to the machine.

The machine further consists in providing means whereby the machine may be quickly disconnected from the motor without affecting the speed of the latter.

30 The invention further consists of certain novel features of construction and arrangement of parts which will be fully understood by reference to the description of the 35 drawings and to the claims to be hereinafter given.

For the purpose of illustrating the invention one preferred form thereof is illustrated in the drawings, this form having been 40 found to give satisfactory and reliable results although it is to be understood that the various instrumentalities of which the invention consists can be variously arranged and organized and that the invention is not 45 limited to the precise arrangement and organization of the instrumentalities as herein shown and described, except as required by the scope of the appended claims.

Of the drawings:

50 Figure 1 represents an elevation partly in section of a device embodying the principles of the present invention.

Fig. 2 represents a vertical section on line 2, 2 on Fig. 1.

55 Fig. 3 represents a vertical section on line 3, 3 on Fig. 1.

Fig. 4 represents a vertical section on line 4, 4 on Fig. 1, and

Fig. 5 represents an elevation of the switch for controlling the operation of the 60 electromagnetic clutch mechanism between the motor and the machine.

Similar characters designate like parts throughout the several figures of the drawings.

In the drawings, 10 is a portion of the frame of a machine provided with a hub 11 and having revolvably mounted in said hub a shaft 12, from which power is supplied to drive the operating parts of the machine. 70 As the various operating parts of the machine form no part of the present invention they are not illustrated.

To the frame 10 is secured a bracket 13, in the outer end of which is mounted an electric motor 14. As this motor 14 may be of any well known construction it is not considered necessary to illustrate its construction. The motor 14 is provided with the driving shaft 15 in alignment with the shaft 80 12 to be driven.

Mounted upon the driving shaft 15 is a sleeve 16 secured to said shaft 15 by a set screw 17, so as to cause said sleeve 16 to revolve with the shaft 15. Mounted upon the 85 sleeve 16 and secured thereto by means of the set screw 17 is a collar 18, having an annular flange 19, in which are mounted a plurality of parallel pins 20, extending through openings in a clutch member 21, slidably 90 mounted upon the sleeve 16.

The pins 20 extend through the openings in the slidable clutch member 21, permitting this member 21 to be reciprocated on the sleeve 16, while insuring its rotation with 95 said sleeve.

The clutch member 21 is provided with an outwardly extending annular flange, the inner wall of which is inclined and adapted to fit the tapered periphery of an annular 100 ring 22, secured to the hub 23 of a spool 24 of insulating material.

This spool is mounted upon a sleeve 25 secured to the driven shaft 12. The outer end of the sleeve 25 is provided with an 105 annular flange 27, the inner wall of which is adapted to fit over the periphery of the hub 28 when the clutch member 21 is moved longitudinally of the sleeve 16.

Within the bore of the sleeve 25 is positioned one end of an intermediate member 29 the opposite end of which is positioned

within the bore of the sleeve 16, the ends of said intermediate member 29 bearing respectively against the ends of the driven shaft 12 and the driving shaft 15.

5 This intermediate member 29 insures the alinement of the shafts 12 and 15 at all times.

Upon the spool 24 is mounted a coil 30 of wire, the windings of which are insulated 10 from each other in any well known manner, and the outer layer of said coil being wound with a layer 31 of paper or some similar material.

Upon the periphery of the spool 24 and 15 coil 30 is mounted a hand wheel 32 by which the shaft 12 may be rotated by hand when desired. The outer end 33 of the coil of wire is connected to the ring 34 and the end 35 of said coil is connected to the ring 20 36. These rings 34 and 36 are secured to the spool 24 by means of the screws 37.

The bracket 13 is provided with an upwardly extending ear 38 to which is secured an insulating disk 39, having secured to its 25 outer face the contact plates 40, 41, and 42.

Secured to the contact plate 40 is a brush 43, the free end of which is adapted to engage the ring 36.

The contact plate 42 has secured thereto 30 a brush 44, the free end of which engages the ring 34. Pivottally mounted upon the disk 39 is an operating lever 45, carrying a bridge 46 adapted to connect the contact plates 41 and 42 when said operating lever 35 is in the position shown in Fig. 5. When the lever 45 is moved into the position shown in Fig. 4, the bridge 46 will be entirely in contact with the plate 41 and the circuit will be broken.

40 The rear end of the operating lever 25 is provided with a projection 47 adapted to abut the stop pin 48 when the device is in operation, and to abut a stop pin 49 when the circuit is broken.

45 The plate 40 is connected by a wire 50 with a binding post 51 on the motor 14 and the plate 41 is similarly connected by a wire 52 with a binding post 53 on said motor 14.

These wires 50 and 52 continue beyond 50 the binding posts 51 and 53 to a suitable source of electric energy, as the battery 54, shown in diagram in Fig. 4 of the drawings.

Between the source of electrical energy 54 and the motor 14 is a switch 55 by which 55 the motor 14 may be thrown into or out of action. When the motor is in operation the operator may throw the operating lever 45 into position shown in Fig. 5, and make a complete circuit through the coil 30, thus 60 magnetizing the sleeve or core 25, and thereby drawing the slidable clutch member 21 into engagement with the tapered periphery of the ring 22.

As long as the electric current passes 65 through the coil 30 the clutch members 21

and 22 will be retained in firm contact with each other and the machine shaft 12 will be driven from the motor 14 by means of the driving shaft 15.

The movement of the operating lever 45 70 to complete the circuit through the electric magnet will cause the immediate movement of the slidable clutch member 21 into contact with the ring 22, so that the shaft 12 will be immediately rotated at the same 75 speed as that of the motor shaft 15.

By moving the shaft 45 into the position shown in Fig. 4 the circuit to the electric magnet 30 will be broken and the clutch members 21 and 22 will become separated 80 thereby permitting the shaft 15 and the electric motor 14 to revolve at full speed without transmitting movement to the driven shaft 12. This shaft 12 may be brought to a full stop by the operator using 85 the hand wheel 32.

With the lever 45 in the position shown in Fig. 4, the operator may rotate the shaft 12 by means of the hand wheel 32. This makes a very quick acting clutch, particularly desirable for machines to be driven without variation in speed. By the use of this magnetic clutch a motor may be connected in alinement with the machine shaft, and drive the main shaft of the machine 95 without the interposition of other instrumentalities.

On sewing machines and the like the current may be secured from the ordinary electric light sockets. By connecting the motor 10 directly to the machine as shown and described herein the shafts, counter shafts, pulleys, and belts, usually used to operate machinery of this class would be entirely dispensed with.

We believe that the many advantages and the operation of the invention will be fully understood without any further description.

Having thus described our invention, we 1 claim:

1. In a device of the class described, two alined shafts; means for driving one shaft; two clutch members, one on each shaft; a member interposed between said shafts and alined therewith, having the ends thereof positioned in sockets axially disposed relatively to said clutch members; and magnetic means on the driven shaft for moving one of said clutch members into coacting relation with the other.

2. In a device of the class described, two alined shafts; means for driving one shaft; two clutch members, one on each shaft; a revoluble member interposed between said shafts and alined therewith; and magnetic means on the driven shaft for moving one of said members into coacting relation with the other.

3. In a device of the class described, a driving shaft; a driven shaft; a sleeve se-

- cured to said driven shaft; an electromagnet secured to said sleeve; a clutch member secured to said magnet; means for controlling the operation of said electro-magnet; a hand wheel surrounding the electro-magnet whereby the rotation of the driven shaft may be manually stopped when the clutch members have been disengaged; and a slidable clutch member on said driving shaft adapted to be moved by said magnet into coacting relation with said magnet clutch. 5
4. In a device of the class described, a driving shaft; a driven shaft; a sleeve secured to said driven shaft and having an annular flange; an electromagnet secured to said sleeve; a clutch member secured to said magnet; means for controlling the operation of said electro-magnet; and a slidable clutch member on said driving shaft adapted to be moved by said magnet into coacting relation with said magnet clutch, and having a hub adapted to fit within said annular flange. 10
5. In a device of the class described, a driving shaft; a driven shaft; a sleeve secured to said driven shaft; a member of insulating material revoluble with said sleeve and provided with two peripheral flanges; a wire coil on said member between said flanges; a source of electric energy; a switch between said source and said coil; a tapered ring secured to the hub of said flanged member; and a slidable member on the driving shaft having an annular flange adapted to be drawn into contact with the periphery of 15 said ring whenever said coil is energized. 20
6. In a device of the class described, a driving shaft; a driven shaft; a sleeve secured to said driven shaft; an electromagnet inclosed in a member of insulating material secured to said sleeve; an annular clutch member secured to said magnet inclosing member and having a conical periphery; means for controlling the operation of said electro-magnet; and a slidable clutch member on said driving shaft adapted to be moved by said magnet into coacting relation with said magnet clutch, and having a flange provided with an inner wall adapted to coact with the periphery of said annular member. 25
7. In a device of the class described, a driving shaft; a driven shaft; a flanged member of insulating material revoluble with said driven shaft; a wire coil on said flanged member; a source of electric energy; a switch between said source and said coil; a tapered ring secured to said flanged member; and a slidable member on the driving shaft having an annular flange adapted to be drawn into contact with the periphery of 30 said ring whenever said coil is energized. 35
8. In a device of the class described, a driving shaft; a driven shaft; a sleeve secured to said driven shaft and having an annular flange; an electromagnet inclosed in a member of insulating material secured to said sleeve; a clutch member secured to said magnet inclosing material, and having a conical periphery; a sleeve on the driving shaft; a slidable clutch member on the driving shaft sleeve provided with a hub adapted to fit within said annular flange and having a projecting flange adapted to coact with the conical periphery of the other clutch member; and means for controlling the operation of said electromagnet. 40
